United States Patent Office.

SAMUEL LARKIN, OF BRIDGEPORT, CONNECTICUT, ASSIGNOR TO BRIDGEPORT KNITTING COMPANY, OF SAME PLACE.

Letters Patent No. 80,866, dated August 11, 1868.

IMPROVEMENT IN KNITTING-MACHINES.

The Schedule referred to in these Letters Patent and making part of the same.

TO ALL WHOM IT MAY CONCERN:

Be it known that I, SAMUEL LARKIN, of Bridgeport, in the county of Fairfield, and State of Connecticut, have invented a new Improvement in Knitting-Machines; and I do hereby declare the following, when taken in connection with the accompanying drawings, and the letters of reference marked thereon, to be a full, clear, and exact description of the same, and which said drawings constitute part of this specification, and represent, in—

Figure 1, a side view.

Figures 2, 3, and 4, detached parts to illustrate my improvement; and in Figure 5, the work which the machine is desired to produce.

This invention relates to an improvement in the knitting-machine invented by J. A. and H. A. House, and for which Letters Patent of the United States were granted, bearing date March 13, 1866, of which said invention the assignees of this present invention are also the assignees.

The object of this invention is to knit in stripes with two colors, that is, to make alternate stitches with different-colored threads.

In the original machine, when two threads are used, a stitch is necessarily formed from each thread upon each needle, which, if two threads are used, knits in stripes across the work and not in vertical stripes. This invention, therefore, to accomplish the desired object, consists in combining with the hooks and needles a lever or finger, which holds the thread away from and so as to pass alternate needles, so that the same color is brought continually to the same needle, and thus vertical stripes are knit.

To enable others to construct and use this improvement, I will proceed to describe the same as illustrated in the accompanying drawings.

A is the bed-plate, α the needles, arranged in a continuous chain, and operated in like manner as in the original patent of House.

B is the knitting-hook, arranged upon the arm C, and upon which said arm the presser-finger D is also arranged, the hook forming the stitches and the finger D pressing them down, all in like manner as in the original patent of House, receiving the thread through the guides E.

Each operation of the hook forms a stitch, with two threads and two hooks, as denoted in fig. 2, and as described in the original patent, two stitches being formed at the same time.

When knitting with two threads of the same color, the stitches are formed continually one above the other, each successive line of stitches around the work being formed from alternate threads.

If colored threads are used, it will be seen that the threads will necessarily lie so as to form a simple, plain ring around the work, but in using threads of two colors, it is desirable, at many times, that it be wrought in stripes, as seen in fig. 5. On the original machines this was impossible, but by my improvement I am enabled so to do, and this is accomplished by, at each movement of the needles, holding the threads back, so that they do not pass under the hook of the next needle, but skip over to the second, that is, the threads respectively taking alternate needles.

To accomplish this, I arrange a lever or fringe, d, which, hung at f on the carrier, is operated by a cam, b, so that, as the presser-finger goes down, and immediately before the chain of needles moves, the finger d is thrown forward from the position in fig. 1 to that in figs. 2 and 4, so as to carry the thread back of the needles, the red line denoting the thread thus held back, whereas, without the finger d, the thread would be carried under the hook, as denoted by the broken line, fig. 2. So soon as the needles have moved one point, and the carrier rises, the finger d falls back, as denoted in fig. 1, and the threads are brought up under the second hook, as denoted by the red line, fig. 1, and thus each stitch of like color is formed upon alternate hooks, each color skipping the needle upon which the other forms a stitch, so that continually the same color falls under the hook of the same needle at each revolution of the chain.

If more than two colors are used, the finger operates in the same way, the needles being carried along so as always to bring the same color upon the same needle.

If, after knitting a short distance in this manner, it be desirable to alternate, so that a short stripe of one color shall be made above a short stripe of another color, and thus form checks, as it were, it is only necessary to adjust the chain of needles one point, and the colors will be reversed upon their needles. Thus, by the simple application of the finger *d*, I am enabled to produce upon this machine a great variety of work.

Having thus fully described my invention, what I claim as new and useful, and desire to secure by Letters Patent, is—

The finger *d*, constructed and operated as described, so as to carry the threads over any given number of needles to form the stitches in the relative position to each other, substantially as set forth.

SAMUEL LARKIN.
